CLAIM

I claim the ornamental design for a package, as shown and described.

DESCRIPTION

FIG. 1 is a plan view of a package in an unassembled configuration, illustrating the unassembled components of the package next to one another.

FIG. 2 is a perspective view of the package in a closed configuration.

FIG. 3 is a perspective view of the package in a partially open configuration.

FIG. 4 is a side view thereof.

FIG. 5 is a perspective view of the package in a fully open configuration.

FIG. 6 is a plan view of the package in a closed configuration with a tear strip removed and remote from the remainder of the package; and,

FIG. 7 is a plan view of the package in an open configuration with the tear strip removed and remote from the remainder of the package.

The broken lines in the figures depict unclaimed portions of the package only and form no part of the claimed design.

1 Claim, 7 Drawing Sheets
